LAP

Alexander P. McArthur, Chicago, Ill.

Application December 1, 1943, Serial No. 512,455

9 Claims. (Cl. 51—184.3)

The process of lapping holes to finish them very accurately for precision work, as usually practiced, is a slow and costly matter; it is necessary to remove the laps from time to time to supply additional lapping compound; the laps frequently freeze in the holes despite the most careful attention on the part of the workmen; adjustment to compensate for wear is difficult; and, where a hole has a bottom, it is difficult to make a square corner there because the lapping compound accumulates in the bottom of the hole and soon wears away the corner of the lap and leaves it rounded.

The primary object of the present invention is to make possible rapid and accurate lapping of holes, thereby greatly increasing output and greatly reducing costs.

In my endeavors to achieve my main object, I conceived several novel features each of which in itself is an improvement over prior practice while, together, they overcome all of the aforesaid objections, as well as others.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is an elevational view of a lap embodying the present invention, positioned in a hole to be lapped; Fig. 2 is a view similar to Fig. 1, showing the lap as having made a quarter turn from the position it occupies in Fig. 1; Fig. 3 is a section on line 3—3 of Fig. 1, indicating, as does also Fig. 2, a lapping compound in pockets outside of the lap; and Fig. 4 is a perspective view of the adjusting wedge.

In the drawing I have illustrated a device containing all of the novel features and for the sake of brevity, I shall describe in detail only this highly developed form; although it will be understood that each feature in itself improves the ordinary lap. The lap is composed of a body member 1, a shank 2 and a wedge block 3. The body member is made from a solid cylindrical block of any suitable metal. The shank is preferably screwed on so that it may be applied to different body members. A central slot 4 extends up through the bottom of the body member, across a diameter of the latter. This slot extends well up toward the top of the body member and there is merged into a narrower slot 5 that forms a continuation thereof. These two

slots transform the body member into a heavy hairpin whose two legs 6 and 7 have a spring action which presses them against opposite sides of a hole when entered in the latter after having been squeezed together a little. The wedge is preferably a block that fits slidably in the slot 4 and has a tapered nose partially entered in the slot 5. A light tap on the wedge drives it a little farther into the slot 5, spreading the legs apart. By this means compensation for wear may be quickly and easily made. In order to provide the upper part of the body member with a spring action similar to that given the lower end by the legs 6 and 7, I cut two other slots 8 down through the upper end of the body member. The slots 8 lie in planes that are on opposite sides of and parallel to the plane of the slot 4 and they extend down far enough to overlap the upper end of the slot 4. Thus there are formed at the upper end of the body member lips or legs 9 and 10 lighter than and extending in the opposite direction from the legs 6 and 7, respectively. The body member is mutilated peripherally in those areas where the slots open out, preferably by flattening, as indicated at 11, so that when the body member is inserted in a hole A in a piece of work B, the cylindrical wall bounding the hole forms with the body member a pair of substantial pockets C extending throughout the length of the latter. In the periphery of the body member are two deep channels 12 each of which extends from the lower end of one of the flattened areas to the upper end of the other such area. The two channels are inclined in the same direction.

It will be seen that while the slots 8 are narrow the slot 4 is much wider. This is for the purpose of providing the lap with a central chamber large enough to contain all of the lapping compound needed to perform any ordinary lapping operation.

In the use of the lap the stem or shank is fixed in the chuck or holder of a drill press or other power device by means of which it can be rotated rapidly; the work being supported in any usual or suitable way. The lapping compound D may be applied to the lap either before or after it is attached to the machine. In any event, after the lap, carrying its charge of compound, is inserted in the hole to be lapped and is rotated at high speed, the compound is driven out into the pockets C through centrifugal action. In this way the compound is applied positively to the surface to be lapped and need only

be rubbed against such surface by the revolving lap.

The heat generated by the lapping action soon causes the compound to become very fluid, so that it runs downward in the pockets. However, instead of being left free to escape, the compound is picked up by the channels and is forced up the same until it is discharged into the upper ends of the pockets. In order to secure this result it is of course necessary that the lap be rotated in the direction that makes the lower ends of the channels the advance ends. It will be seen that not only do the channels cause the lapping compound to be recirculated through the pockets, but they also act as distributing means that leave a coating of compound on the surface that is being lapped as the streams of compound travel upwardly and laterally along the channels while in contact with said surface.

The mutilation of the cylindrical surface of the lap to provide areas of considerable angular width extending throughout the length of the body member of the lap serves another highly useful purpose. All laps that I have heretofore used frequently freeze in the work, causing a loss of time and creating the danger that the work will be spoiled. The presence of the idle zones on the lap gives every part of the surface in the piece of work a breathing spell, as it were, twice in each revolution of the lap. Whatever the reason therefor may be the fact is that with my improved lap freezing of the same in the hole is eliminated.

Initial adjustment or compensation for wear may be made, as before stated, by simply tapping the wedge until the lower end of the lap has expanded sufficiently. This operation causes the free ends of the lighter legs or lips 9 and 10 to approach each other, contracting the upper end of the body member. But, when the lower ends of the legs 6 and 7 are pressed together to enter the lap in a hole, the two legs on each side act as a beam which rocks about the wedge as a fulcrum, thereby causing the free ends of the legs 9 and 10 to swing apart and to press against the surrounding wall when the lap is pushed all the way down.

There are two factors which make it practicable to lap sharp corners at the bottom of a hole. In the first place, compound cannot collect in the corners while the lap is down because it will be scooped up by the lower ends of the channels as soon as the channels come within range. Also, should the corner at the bottom of the lap become slightly rounded, the sharpness thereof can easily be restored by simply grinding a little off the flat bottom of the lap. The nature of the lap is such that its efficiency will not be diminished by a few of such grindings.

A further valuable characteristic of my lap is that it may be made in a comparatively few sizes extending over a wide range, while any intermediate micrometer size may then be obtained by trimming down the nearest larger size. Thus, for example a $5\frac{1}{8}$ " lap may be cut down as much as $1\frac{1}{8}$ " without interfering with the proper working of the channels or detracting from the effectiveness of the spring elements of the device. The larger the lap the greater the amount of reduction can be made in the diameter to produce a wanted size. Thus a 2" lap may be cut down as much as $1\frac{1}{8}$ ", if necessary.

I claim:

1. A tool of the character described, comprising a cylindrical body member having a plurality

of longitudinal peripheral areas mutilated to form with a surrounding cylindrical wall in a piece of work a plurality of long longitudinal pockets, and having, also, a diagonal peripheral uninterrupted channel leading from the lower end of at least one of said areas to another at a point well above the lower end of the latter, so as to connect directly with two of said pockets, and being biased in the direction to cause lapping compound to be conveyed from the lower end of at least one pocket into another pocket while said member revolves during a lapping operation.

2. A tool of the character described, comprising a cylindrical body member having diametrically opposed longitudinal peripheral areas mutilated to form with a surrounding cylindrical wall in a piece of work a pair of long longitudinal pockets, and having, also, a single diagonal peripheral channel leading from the lower end of each of said areas to the other area at a point well above the lower end of the latter area, so that each of said channels communicates with both of said pockets at points within the length of the body member, said channels being biased in the same direction so as to cause each continually to feed lapping compound from the lower end of one pocket into the other pocket while said member revolves during a lapping operation.

3. A tool of the character described, comprising a cylindrical body member having diametrically opposed longitudinal areas flattened to form with a surrounding cylindrical wall in a piece of work a pair of long longitudinal pockets, and having, also, a diagonal peripheral channel leading from each of said areas to the other, all of said channels being biased in the same direction so as to cause each to convey lapping compound from one pocket to a higher point in the other pocket while said member revolves during a lapping operation.

4. A tool of the character described comprising a cylindrical body member having a deep slot extending upwardly through the bottom and across a diameter of said member, the periphery of said member being cut away along longitudinal lines beside said slot to form with the surrounding wall of a piece of work pockets of substantial size extending lengthwise of said member and communicating with said slot, and said member having, also, peripheral diagonal channels each extending from the lower end of one of the pocket-forming regions to the upper end of the other such region, all of the channels being inclined in the same direction.

5. A tool of the character described comprising a cylindrical body member having a deep slot extending upwardly through the bottom and across a diameter of said member, the periphery of said member being mutilated to create parallel longitudinal flat faces each bisected by said slot and adapted to form with a surrounding cylindrical wall of a piece of work pockets extending lengthwise of said member and communicating with the slot, and said member having, also, peripheral diagonal channels all extending in the same direction from the lower end of one of said flat faces to the upper end of the other flat face.

6. A tool of the character described, comprising a cylindrical body having a deep slot extending upwardly through the bottom and across a diameter of said member, the periphery of said member being cut away along longitudinal lines beside said slot to form with the surrounding wall of a piece of work at least one pocket extending lengthwise of said member and communicating

with the slot, and said member having, also, other slots entering the upper end of said member in planes parallel to and on opposite sides of the plane of the central slot and being deep enough to extend down past the upper end of the latter slot.

7. A tool of the character described, comprising a cylindrical body having a deep central slot extending upwardly through the bottom and across a diameter, the periphery of said member being cut away along longitudinal lines beside said slot to form with the surrounding wall of a piece of work pockets extending lengthwise of said member and communicating with said slot, said member having, also, other slots entering the upper end thereof and arranged in planes parallel to and on opposite sides of the central slot and being deep enough to extend down past the level of the upper end of the central slot, the central slot merging at its upper end into a narrower slot that forms a continuation thereof, and a wedge slideable in said central slot and partially entered in the said narrower slot.

8. A tool of the character described, comprising a cylindrical body of spring metal having a deep central slot extending upwardly through the

bottom and across a diameter, said member being flattened on opposite sides along said slot to form with the surrounding cylindrical wall of a piece of work pockets extending lengthwise of said member and communicating with said slot, the central slot merging at its upper end into a narrower slot that forms a continuation thereof; said member having, also, two other slots entering through the upper end thereof and arranged in planes parallel to and on opposite sides of the central slot and being deep enough to extend down past the juncture of the central slot and the said narrower slot to produce spring lips at the upper end of said member; and a wedge slideable in said central slot and partially entered in said narrower slot to exert a pressure tending to spread the lower part of said member and to serve as a fulcrum to cause the free ends of said lips to swing outwardly when the lower end is contracted to enter a hole to be lapped.

9. A device as described in claim 8 in which there are also peripheral channels in said member biased in the same direction and each leading from the lower end of one flattened area to the upper end of the other such area.
